AUTOMATIC TONG

Whitney C. Babin and Raymond A. Ames, Beaumont, Tex., assignors to Beaumont Texan Tool Company, Beaumont, Tex., a corporation

Refiled for abandoned application Serial No. 470,449, July 24, 1930. This application October 29, 1934, Serial No. 750,567

3 Claims. (Cl. 81—53)

The invention relates to an improvement in automatically releasable make up tongs of the type which are used in making up drill stem and casing in the rotary method of drilling wells.

5 The invention is in the nature of an improvement over the disclosure in the applications of Whitney C. Babin, Serial No. 364,635, filed May 20, 1929, for a Make up tong, Serial No. 447,118, filed April 25, 1930, for Combination make up and break out tong.

It is one of the objects of the invention to provide a tong which will release its grip upon the pipe when a predetermined torque resistance is encountered.

15 It is another object of the invention to provide a tong wherein one of the jaws will be released from engagement with the pipe when the resistance of the pipe to turning exerts a predetermined pressure.

20 Another object of the invention is to provide a tong having a linkage construction which will permit pivoting movement of the jaw with respect to the handle and release of such jaw.

Another object of the invention is to provide 25 a tong having two pivotal jaws, one of which is adapted for engagement with the pipe by pivotal movement of the handle with respect to the other jaw and also adapted for release from the pipe when the handle negotiates a predetermined degree of pivoting.

A still further object of the invention is to 30 provide a linkage which is adapted to operate and release one of the pivotal jaws of the tong when a predetermined resistance is encountered, in combination with means to prevent such release if desired.

Another object of the invention is to provide 35 a tong which will be automatically releasable and will adjust itself to slight variations in the size of the pipe that is being encountered without affecting the automatic releasing operation of the tong.

A still further object of the invention is to 40 provide a clasp which is carried by the handle and is adapted to engage with an extension portion on one of the jaws so that the jaw may be moved into engagement with the pipe but released from the clasp by movement of the handle.

50 Other and further objects of the invention will be readily apparent to those skilled in the art when the following description is considered in connection with the accompanying drawings wherein:

55 Fig. 1 is an edge elevation of a tong embody-

ing the invention with one portion thereof shown in section.

Fig. 2 is a side elevation showing the tong in position to grip the pipe.

Fig. 3 shows the head of the tong as embodied in a modified form of the invention.

Fig. 4 is a sectional view through the clasp members which are used to engage the jaw.

Fig. 5 is another modified form of the head which may be used to engage different sizes of pipe.

Fig. 1 shows a handle 2, which is provided with a plurality of openings 3, whereby the handle may be connected to the make-up post which is usual construction in connection with power-driven make-up and break-out tongs. One type of make-up post is shown in my co-pending application, Serial No. 447,118.

This application is a re-filing of a previous application, Serial No. 470,449, dated July 24, 1930.

The forward end of this handle carries a pin 4, to which is pivoted the head or jaw member 5. This head 5 is arranged to receive the pivot 7, which carries the second jaw member 8. A pin 9 carries a wire 10, which serves to engage the bolts 4 and 7 to prevent their normal removal or displacement. The shank of this jaw member or hook 5 might be said to be that portion between the pins 4 and 7 designated by the character 81.

The head 5 in Figs. 1 and 2 is shown as made up of a single integral piece and has the contact face 11 and the small handle 12 so that it may be readily placed in contact with the pipe or removed therefrom. The body 14 of the head 5 is formed as a yoke having the branches 15 and 16, through which the pins 4 and 7 project. Between these branches the jaw 8 is adapted for pivotal movement. These branches 15 and 16 are formed with an arcuate rearward surface 18, whose function will be later described.

The jaw 8 has a pipe engaging die 20 therein which is retained in place by a locking screw or other means 21. Particular attention should be directed to the shank or extension 23, which is formed on the rearward end of the jaw 8 beyond the pivot pin 7. This extension 23 is of arcuate formation as at 24 and is provided with the inclined surfaces 25. The beveled surface 25 is also arcuate in formation as it follows the curvature of the portion 24. A clasp 30 is pivoted at 31 to the handle 2 at a point below or outside of the pin 4. This clasp comprises two arms or links 31 which are disposed on opposite sides of the handle and are provided with recesses 32, which

are adapted to fit over the head 33 of the pin 34, which passes through the handle 2. A set screw 35 and nut 36 serve to adjust the relative position of the arms 31 with respect to the handle. A bolt 38 is adapted to pass through both of the arms 31, which are held thereon by means of the springs 39 and the nuts 40. The inward movement of the arms 31 is restrained by means of a spacer 42, which fits in recesses 43, which are formed in the opposite arms. In this manner the springs 39 tend to move the arms inwardly with the ball 33 as the fulcrum or pivot point. The spacer 42 limits this inward movement so that the outer ends 45 of the arms are spaced apart a sufficient distance to receive the jaw 8 or rather the extension web thereof. The arcuate portion 24 is supported by the web 26 which is adapted to project between the two arms 31. Suitable rollers or anti-friction members 47 are carried on each arm, these rollers being adapted to travel upon the beveled face 25 of the arcuate extension 24.

The operation of the tong is as follows: The handle 2 is mounted by means of a bolt or other member passing through the openings 3 and upon the make-up post. The tong is then pivoted horizontally about the make-up post as a center so that the head 5 passes into contact with the pipe which is to be manipulated. The surface 11 contacts the pipe as does the die 20. It is intended, however, that the head 5 will be moved clockwise about the pin 4 to such an extent that the opening between the face 11 and the die 20 will be sufficient to receive the pipe. When this position has been accomplished the rotary table which carries the make-up post is started. This causes rotation of the handle 2 in a clockwise direction. The face 11 and the die 20 are thus caused to grip against the pipe so that the handle then begins to pivot about the pin 4 as a center. In view of the fact that the clasp 30 is spaced away from the pin 4 it will continue its movement. The rollers 47 engage upon the beveled face 25 and tend to pivot the jaw 8 about the pin 7. This pivoting movement causes the die 20 to securely grip against the pipe which is to be turned so that any continued movement of the handle 2 tends to increase the gripping force upon the pipe. It is to be understood that the force of the rollers 47 on the face 25 tends to separate the two arms 31 so that the rollers 47 may pass over the maximum width of the beveled face 25. This separating action, however, is resisted by the springs 39 so that the turning moment is exerted upon the jaw 8 by the handle 2 through the arms 31. In this manner the pipe is screwed into position with the adjacent section which is being held stationary. The operation of the rotary table can not be controlled very accurately and it often occurs that where the tong is securely gripped to the pipe that the continued rotation of the rotary table will cause the threads of the pipe coupling or tool joint to be mutilated or destroyed.

However, with the present tong the tension on the springs 39 may be adjusted by means of the nuts 40 so that when a predetermined pressure has been exerted by the die 20 upon the pipe the compression on the springs 39 will be overcome and the arms 31 will tend to separate, allowing the rollers 47 to travel up and over the beveled face 25. In other words, when the pipe is made up to a pressure equal to that which may be safely carried by the threads on the pipe or tool joint, continued rotation of the handle

does not accomplish any further rotation of the pipe because the arms 31 begin to separate and after rotation is continued the rollers 47 will completely release the arcuate portion 24 of the jaw 8. When this release occurs the tong will swing free from the pipe and the operator is then advised that he may discontinue the rotation of the rotary table. It seems apparent that by proper adjustment of the compression on the springs 30 that any desired torque may be transmitted to the pipe which is being made up as the tension on the spring governs the amount of resistance to separation of the arms 31 and accordingly the resistance at which the jaw 8 will be released.

Attention is also directed to the beveled face 25' which is traversed by the rollers 47 as they move to release position. When the rollers have been separated the maximum amount they then contact the face 25' so that the pressure of the springs 39 through the rollers 47 tends to move the jaw 8 in a counterclockwise direction so that the jaw will be moved to an off position away from the pipe and insure release. When the clasp is free from the jaw the springs instantly close it so that it is impossible for the tong to rebound and grasp the pipe a second time unless it has been reset. This is very important because if the tong were to rebound and grasp the pipe a second time before it were reset there would be no release and damage or injury would result. In other words the springs 39 have a double purpose as they compress when the arms 31 separate to permit the tong to release the pipe, and instantly after the rollers 47 pass the crown of the cam between the faces 25 and 25' the springs expand to kick the jaw 8 away from the pipe and retain the tong in open position until it is reset.

The arcuate formation of the portion 24 and the beveled face 25 is provided for the special purpose of adapting the tong to slightly different sizes of pipe. In this manner where a tool joint or pipe has been worn considerably and is of less diameter than a new pipe or joint, it will be necessary for the tong to grip this slightly smaller joint with the same force as it would grip a standard size pipe or joint. Thus the die 20 will pivot inwardly a greater distance toward the face 11 with the small joint than it would with the standard size joint. When this occurs, the roller 47 will remain on the beveled face 25, but instead of traveling along the face in the position shown in Fig. 2 they will travel along the face at a point slightly lower down, or, in other words around the curve a greater distance from the end 27 of the jaw, but the compression on the springs 30 will remain the same so that the tong will operate upon slightly different sizes of pipe by reason of this automatic adjustment.

The rotary is brought to a stop so that the handle 2 remains stationary and the jaw 8 having been forced into off position and into contact with the surface 18, the operator grasps the handle 12 on the head 5 and brings the end 50 of the clasp fingers 31 also into contact with the surface 18. The head 5 is then pivoted clockwise about the pin 4 which opens the space between the die 20 and face 11, so that the tong may be passed around the next piece of pipe. This action automatically forces the clasp and rollers to straddle over the web 26 into position of adjustment to whatever size joint may be in contact position at the instant.

Then, as he reverses the movement of the head 5 in the opposite direction, placing the head 5 or hook around the pipe, the rotary is started which moves the handle 2 clockwise about the pin 4, bringing into play the combined action of all these parts which keeps the tong in forceful contact with the pipe until the desired torque is reached. This action of the parts in resetting the tong is completely automatic except for the act of the operator in grasping the handle 12 and throwing the clasp into position, then moving the head 5 first in a clockwise direction about the pin 4 and then in the reverse direction and into position about the pipe.

When it is desired to use the tong for breaking out, it is only necessary to turn the tong over and fasten the clasp arms 31 to the jaws 8 so as to prevent it from tripping and still retain the automatic adjustment feature to accommodate the variation in sizes of tool joints. The jaw and clasp are fastened together by the operator who aligns the opening 53 in the jaw 8 with openings 52 in the clasp arms 31 and inserts a suitable pin. The clasp 30 will be securely locked so that the tong cannot trip or release. The rotary and handle 2 now remain stationary as before, the operator grasps the handle 12, on the head 5, and rotates or pivots the head 5 anti-clockwise about the pin 4, thus opening the tong to receive the pipe in contact with the face 11 on the head 5 and the die 20. The rotary is then started which carries the handle 2 clockwise about the pin 4. The jaw 8, and the clasp 30 being joined together form a linkage with the handle 2 and the shank of the jaw 5 to exert a pressure on the die 20 to engage the pipe. This combined action of all these parts linked together being further strengthened by the action of the fulcrum formed about the pin 4 by the handle 2 and the head 5, imparting an automatic adjustment about the pipe and also effecting a scissor-like gripping force, which is one of the most valuable features of the invention. When used for breaking out the tong may be swung from a catline and operated from the cat or breakout head on the draw works if desired.

Figs. 3 and 5 show a modified form of the head 5, which may be used in connection with the tong if desired. The primary purpose of these modifications is to provide a head which will be adjusted to accommodate pipes of different diameter or different sizes. In Fig. 3 the head is indicated generally by the reference character 60 and comprises the shank 61 which receives the pins 4 and 7, the same as in the modification shown in Figs. 1 and 2. The head portion, however, is arranged for adjustment with respect to the shank 61. This head or jaw 62 is pivoted on the pin 63 at a point beyond the pin 7. In this manner the face 11 is adjustable and can be moved toward or away from the die 20, which is carried on the jaw 8. It is intended that the adjustment of the head 62 will be such that it may be set and released very readily. This is accomplished by means of a pawl 65 pivoted on the pin 66 and formed with teeth 67. These teeth are arranged to cooperate with teeth 68 formed upon a finger 69 on the head 62. The handle 12 is the same as provided on the modification shown in Fig. 2. With this construction it seems apparent that the handle 12 may be used to adjust the position of the head 62 so that it will accommodate any size of pipe. When it is desired to reset the head 62 for another size it is only necessary to release the pawl 65 so that the teeth

67 and 68 will be disengaged and the head may then be pivoted about the pin 62. In the operation of the tong the modified heads of Figs. 3 and 5 will be manipulated the same as explained in connection with the Fig. 1 embodiment. However, care may be necessary not to disturb the adjustment of the jaw nose if the same size tool joint is to be gripped.

The modification shown in Fig. 5 is somewhat similar to the modification just described except that the pawl 65 has been replaced by a lever 70 pivoted at 71 and provided with a lug 72. The handle 12' has been modified to comprise a lug 73 which is adapted to engage with the lug 72. The handle 12 is pivoted at 74 and in this manner when a clockwise pressure is exerted on the handle 12 the lugs 72 and 73 will engage so that the lever will pivot about its pin and disengage the teeth 67 and 68. The stop member 75 is provided to limit the forward movement of the handle 12' and a small spring 76 is used to normally retain the lugs 72 and 73 in position. This spring is anchored by means of the bolt 76'.

The invention broadly embodies a four-bar linkage constituting the pivots 31', the rollers 47, 25 and the pivot pins 4 and 7. In this linkage the clasp 30 and the curved portion or shank 23 of the jaws 8 serve as two members while the portion 30 of the handle, between the points 4 and 31' and the portion 81 of the shank of the head 30 5, between the points 4 and 7, serve as the other two links. The portions 30 and 81 are of less length than the links 30 and 23 so that upon movement of the handle 2 the die 20 is caused to pivot about the pin 7. In this way a leverage is 35 obtained which will cause an enormous gripping pressure upon the pipe and at the same time the linkage is releasable by the spreading of the arms 31 due to a predetermined pressure upon the handle.

It is to be understood that various modifications and alterations may be made in the structure without departing from the spirit of the invention which is believed to be here disclosed as a practical and satisfactory design which will serve the purpose of an automatically releasable tong.

We claim:

1. A pipe tong of the automatically releasable type composed of parts including two jaws, a handle and a clasp, said parts being connected in the form of a four-bar linkage, one of said connections being adjustable automatically as a function of the size of the pipe engaged.

2. In an automatically releasable power driven pipe tong including a releasable jaw, a connecting link between the releasable jaw and the handle, said link including a pair of arms, and means to normally cause said arms to contact the jaw but releasable when a predetermined torque is exerted on the handle.

3. A pipe tong of the character described including a jaw member, a second jaw and a handle pivoted to said first jaw at different points, a link connecting said handle and said second jaw so that movement of said handle will cause relative pivoting of said jaw members, and means whereby said link will be releasable from said jaw upon exertion of a predetermined thrust on said tong, and means on said first jaw to reset said link with respect to said second jaw when said handle is retracted.
